ANTIAIRCRAFT AND MACHINE GUN MOUNT

Roy Benjamin Lindsey, Phoenix, and George Frock, Glendale, Ariz., assignors of one-third to Harry J. Mauler, Phoenix, Ariz.

Application June 3, 1942, Serial No. 445,626

3 Claims. (Cl. 89—37)

This invention relates to improvements in gun mounts, and pertains particularly to an improved anti-aircraft and machine gun mount of a collapsible and portable nature.

A particular object of the present invention is to provide an anti-aircraft and machine gun mount having an ammunition cradle in which the receptacle for the ammunition belt is supported, which will maintain the ammunition belt receptacle in correct position at all times while the gun is being fired, regardless of the angle of the gun, such ammunition carrying means taking the place of and, consequently, eliminating the gunner's helper.

Another object of the invention is to provide in a gun mount of the character stated a novel construction wherein the oscillatable ammunition receptacle cradle is rocked by and in response to the oscillatory movements of the gun.

Still another object of the invention is to provide a demountable and portable anti-aircraft and machine gun mount for light and heavy caliber guns which is designed for extreme simplicity and speed of assembling and taking down and which is, at the same time, light of weight yet sufficiently rugged for any usage.

Still another object of the invention is to provide in a gun mount of the character stated a novel base unit or leg unit which may be easily and quickly folded or unfolded for use and which has associated therewith a novel means for locking the legs in extended position for use or in folded position.

The invention will be best understood from a consideration of the following detailed description taken in connection with the accompanying drawings, it being understood, however, that the invention is not to be considered as limited by the specific illustration or description but that such illustration and description constitute a preferred embodiment of the invention.

In the drawings.

Figure 1 is a view in side elevation of the anti-aircraft and machine gun mount embodying the present invention, parts being broken away.

Figure 2 is a view in front elevation of the upper half of the mount structure.

Figure 3 is a view in top plan of the upper half of the structure.

Figure 4 is a vertical section on the line 4—4 of Figure 2.

Figure 5 is a view, partly in elevation and partly in section, of the base structure for the mount.

Figure 6 is a horizontal section on the line 6—6 of Figure 1.

Figure 7 is a horizontal section, looking up, on the line 7—7 of Figure 5.

Figure 8 is a horizontal section on the line 8—8 of Figure 5.

Figure 9 is a detailed section showing the locking relation of the ring and the upper end of a brace arm when the legs are unfolded.

10 Referring now more particularly to the drawings the reference character S generally designates the standard for the present gun mount, while the character C indicates as a whole the ammunition carrier or support and the base assembly for the standard is generally identified by the reference character B.

The standard comprises the vertically disposed lower post 10 which is secured at its lower end to a plate 11 forming a part of the base assembly 20 and is maintained upright by the latter. This lower post is tubular at its upper end and receives the lower end of the upper post or rotating gun support 12, the upper end portion of which is angled to extend obliquely upwardly 25 from the vertical, as indicated at 13. This upper post has in snug encircling relation therewith the adjustable set collar 14 which rests upon the top of the lower post as shown. This collar 14 has threaded therethrough the set screw 15 which engages at its inner end the post 12 so as to maintain the latter in vertically adjusted position. However, the post 12 is permitted free rotation in the upper end of the lower post 10 so that any desired position may be assumed by the gun supported upon the upper post.

35 The upper end of the upper post is formed to provide the trunnion pin cone bearing 16 which receives the trunnion pin of the gun, not shown, which is to be supported upon the mount. The 40 post 12 has threaded through the upper end thereof to extend into the trunnion pin cone 16 the locking or securing screw 17 which engages the gun trunnion pin to secure the latter in the cone and thus firmly lock the gun upon the upper end of the rotatable supporting post 12.

The numeral 18 generally designates a bed or support for the hereinafter described cradle. This bed comprises the horizontal bottom bar 19 with which are integrally connected, at spaced 50 points, the parallel inner and outer trunnion arms 20 and 21 respectively which terminate at their upper ends in the short opposed and aligned trunnions 22.

55 The inner end of the bottom bar 19 of the bed structure is extended to form the axle 23

and this is extended through a suitable bearing passage 24 formed in the obliquely extending upper portion 13 of the gun supporting post 12, just below the trunnion pin cone 16.

Secured adjacent the inner end of the axle 23 is a stop plate 25 which abuts the side of the post 12 and limits the lateral movement of the axle into the bearing passage 24 and the outer end of the axle is provided with a key slot or aperture 26 which receives a securing or locking key 27 which functions to prevent withdrawal of the axle.

The stop plate 25 and the post 12 against which it abuts, are provided with aligned apertures to receive a position retainer pin 28. This functions to prevent rotation of the axle 23 in its bearing.

The numeral 29 generally designates the ammunition receptacle supporting cradle which is carried by the cradle bed 18. This cradle comprises a bottom or base portion 30 from which extends upwardly the frame 31 which is substantially triangular in cross-section and which has one side extending upwardly in the plane of a longitudinal side of the base 30. At the top of this triangular frame 31 and at each end is a trunnion bearing 32 which receives a trunnion 22. Due to the fact that the plane of the arms 20 and 21 is parallel with the angular upper portion 13 of the gun supporting post and that the axis of oscillation for the cradle is offset from one longitudinal side thereof, the cradle hangs or is positioned somewhat behind the standard.

Fixed to the inner end of the cradle frame 31 at the top of the latter is a rearwardly and inwardly extending cradle arm 33. One portion of this arm extends rearwardly, as indicated at 34, while the other portion is angularly related to the rearwardly extended portion 34 and projects laterally so as to extend across and beneath the barrel of a gun placed on the mount. This arm constitutes a regulator or compensating arm and is engaged by the gun barrel to cause the cradle to be tilted or oscillated automatically with the oscillation of the gun barrel so that the ammunition belt will be fed from the ammunition box supported upon the cradle.

The bearings 32 may be of the ordinary sleeve type or they may be roller or ball bearings, as desired, and also the axle 23 for the cradle bed may be welded or otherwise integrally secured to the angular upper end portion of the gun post 12, if such construction should be found suitable.

It will be readily apparent that by providing the angular or oblique upper end portion 13 of the gun supporting post a higher angle of fire for the gun is allowed. This angle for the portion 13 may be of any desired or suitable degree from the vertical. Also, by inclining the bed frame or support for the cradle the cradle is suspended, as previously pointed out, outside the bed and to the rear of the standard so that the ammunition receptacle when placed on the cradle will be in such position that the ammunition belt will feed to the gun without danger of striking any parts of the mount.

The base assembly includes, as previously stated, the base plate 11 upon which the lower post 10 of the standard is supported. This base plate is provided at suitable spaced points around its periphery, preferably three, with bearing blocks 36, each of which has pivotally connected therewith, by means of a pivot pin 37, a supporting leg 38. Each of these legs adjacent its outer end has secured to the under side there-

of a leg shoe 39 which may be of any conventional size or make suitable to the particular standard or mount. Such shoes prevent side movement or "crawling" of the completed mount while the gun is firing.

Each of the legs 38, at its outer end, carries a locking or securing lug 40 which is arranged to be directed downwardly when the leg is in unfolded or operative position so that it will be directed radially outwardly from the lower post 10 when the leg is swung upwardly to folded or inoperative position against the post.

Each leg 38 carries upon its upper side a leg brace arm bearing block 41 to which is pivotally connected, by means of a pin 42, an end of a brace arm 43 for the leg.

The upper end of each brace 43 carries a transversely extending slightly arcuate slide 44 which facilitates locking the brace arm to the post 10.

Secured to the post for cooperation with each slide 44 is a locking block 45 which projects outwardly from the face of the post and which has a channel or recess 46 in its top side and a vertical outwardly facing slot 47 leading into the channel. The radially directed side of each locking block carries the outwardly extending locking ears 48 which are disposed upon the two sides of the slot. As illustrated, each leg 43 is disposed to ride in a slot 47 of the locking block adjacent thereto and the slide element 44 of the leg when moved downwardly on the post enters the channel 46 of the locking block.

Cooperating with the locking blocks 45 is a locking ring 49 which encircles the post 10 and has free sliding movement thereon. This ring has the undercut channel in its lower face, as indicated at 50, whereby is formed an inwardly directed flange 51 which is spaced from the post a distance substantially equaling the radial extent of a locking block from the post. The flange 51 of the locking ring is cut out or slotted, as at 52, at points equi-distantly spaced and equaling in number the locking lugs 45, the slots being of sufficient depth for the locking block ears to pass through into the channel 50.

The channel 50 of the locking ring is also designed to receive the leg lug 40 for the purpose of locking the leg in folded position.

It will be readily apparent that when the legs 38 are unfolded the slide 44 of the leg braces will ride down the post 10 and enter the channels 46 of the locking blocks. The locking ring 49 which is located above the locking blocks, will follow the slides downwardly and, when rotated to proper position, the flange slots of the locking ring will be in position for the locking block ears to pass into the locking ring channel. The locking lugs will, of course, be disposed between the locking ring flange and the post, together with the slides in engagement therewith and, consequently, when the locking ears have entered the channel of the locking ring the ring may be turned slightly so that the ears will pass into a portion of the channel away from the flange slot and function to hold the ring against upward movement.

In order to secure the ring against rotation after it is in leg locking position a suitable aperture is formed through the ring for the extension therethrough of a locking pin or key 53 which extends across one side of a locking lug and thus prevents turning of the ring with respect to the lug.

When the legs 38 are to be folded the locking

ring 49 is released so that it may be slid up on the post 10 away from the lugs or slides, whereupon the legs are folded inwardly against the post, thereby turning the leg lugs outwardly. The leg lugs are then engaged in the channel of the locking ring by passing them through the flange slots 52, whereupon rotary movement of the locking ring will cause the leg lugs to engage over the locking ring flange and thereby secure the upper ends of the legs in place.

From the foregoing it will be readily apparent that in the present invention has been provided a novel and improved mount for guns of the type of anti-aircraft and machine guns, which will support the ammunition belt receptacle in proper working position so that the belt can be fed freely to the gun, regardless of the angular disposition of the latter. This is made possible by the automatic swinging of the cradle on which the receptacle is mounted, through the cooperative action of the cradle and the cradle arm which is engaged by the gun barrel beneath which it extends.

The entire gun mount may also be constructed of any suitable flat or tubular or solid material of suitable composition to withstand the strains which a structure of this type must sustain.

We claim:

1. Mounting means for a gun of a type employing a belt ammunition feed and adapted to oscillate when in use, comprising a standard hav-

ing an upper end portion directed obliquely with respect to the vertical, means at the upper end of said oblique portion facilitating the mounting thereon of a gun of the above type, an elongated support comprising a bottom bar carrying two upwardly extending arms terminating at their upper ends in opposed trunnions, an axle extending from one end of the bar and secured to the angled portion of the upper post, a cradle structure disposed between said arms and comprising a bottom and an upwardly extending frame of triangular cross-section having a straight side extending upwardly in the plane of one longitudinal side of the bottom, bearings at the ends of said triangular frame, said bearings pivotally receiving said trunnions.

2. A gun mount as set forth in claim 1, in which said axle is mounted in a bearing in the oblique portion of said upper post.

3. A gun mount as set forth in claim 1, in which the vertical plane of the axis of oscillation for the cradle parallels the vertical axis of the standard and is offset from that side of the standard toward which the oblique portion of the post bears, and an arm connected with the upper part of the frame of said cradle and extending forwardly and laterally across the opposite side of the standard to engage across the under side of the barrel of a gun supported on the mount.
